UNITED STATES PATENT OFFICE.

JOSEPH H. MACK, OF PASSAIC, NEW JERSEY.

DESIGN FOR A TEXTILE FABRIC.

Application filed July 23, 1925. Serial No. 14,196. Term of patent 3½ years.

To all whom it may concern:

Be it known that I, JOSEPH H. MACK, a citizen of the United States, residing at Passaic, in the county of Passaic and State of New Jersey, have invented a new, original, and ornamental Design for Textile Fabric, of which the following is a specification, reference being had to the accompanying drawing, forming part thereof.

The figure is a plan view of a textile fabric showing my new design.

I claim:—

The ornamental design for a textile fabric, as shown.

JOSEPH H. MACK.
